(57) **CLAIM**

The ornamental design of a tool reversing lever, substantially as shown and described.

DESCRIPTION

FIG. 1 is a perspective view of a tool reversing lever embodying the design of the present invention, a tool being illustrated in phantom.

FIG. 2 is a right side elevational view of the tool reversing lever illustrated in FIG. 1.

FIG. 3 is a left side elevational view of the tool reversing lever shown in FIG. 1.

FIG. 4 is a back side elevational view of the tool reversing lever shown in FIG. 1.

FIG. 5 is a front side elevational view of the tool reversing lever shown in FIG. 1.

FIG. 6 is a top view of the tool reversing lever illustrated in FIG. 1; and,

FIG. 7 is a bottom view of the tool reversing lever illustrated in FIG. 1.

The broken lines shown in FIGS. 1-7 are for illustrative purposes only and forms no part of the claimed design.
